CONCEALED CEMETERY VASE

Joe Weaver, Jr., Indianapolis, Ind.

Application January 13, 1950, Serial No. 138,383

2 Claims. (Cl. 47—41)

1

This invention relates to a cemetery vase, and more particularly to a support for a cemetery vase which may support the vase in a concealed position on a cemetery lot, and will support the vase in an extended or exposed position.

It is an object of this invention to provide a cemetery vase of the kind to be more particularly described hereinafter having a receptacle therefor which is adapted to be engaged in the ground on a cemetery lot, or the like, the cemetery vase being hingedly mounted on the receptacle to be contained therein when the cemetery lot is being mowed or other work being performed on the lot, and the vase may be extended from the receptacle, to be supported thereon when flowers are to be displayed.

Another object of this invention is to provide a combined cemetery vase and receptacle therefor of this kind, wherein the vase is hingedly mounted within the receptacle to be concealed therein by a closure member hingedly mounted on the receptacle and supported in an extended position by the closure member in a selected juxtaposed relation between the closure member and the vase.

A further object of this invention is to provide a concealable cemetery vase and receptacle therefor, of the kind to be described hereinafter, which may be formed at a relatively low price of substantially conventional type and form of material, while providing a suitable and desirable cemetery vase and support, wherein the vase may be substantially fixed in its position in the cemetery plot to be concealed within the ground when it is not desired to be used for supporting flowers. Such a combination provides for the concealing of the vase when the cemetery lot is being worked upon, or when the flowers have been removed from the vase, and the vase may be submerged into the receptacle to prevent the stealing of the vase, as by vandals or the like.

With the above and other objects in view, my invention consists in the arrangement, combination and details of construction disclosed in the drawings and specification, and then more particularly pointed out in the appended claims.

In the drawings:

Figure 1 is a perspective view of the concealable cemetery vase and receptacle constructed according to an embodiment of my invention;

Figure 2 is a perspective view of this invention, with the vase concealed within the receptacle;

Figure 3 is a top plan view of the cemetery vase and receptacle constructed according to an embodiment of this invention, with the vase within

2

the receptacle and the closure member in the closed position;

Figure 4 is a longitudinal section taken on the line 4—4 of Figure 3;

5 Referring to the drawings, the numeral 10 designates generally a combined cemetery vase and receptacle therefor constructed according to an embodiment of my invention. The combined cemetery vase and receptacle is provided 10 for engagement in the ground of a cemetery plot or the like, for containing the vase concealed within the receptacle, when desired, and supporting the vase in an extended position above the receptacle at other times.

15 The combined cemetery vase and receptacle 10 is formed with a substantially rectangular receptacle 11 which is adapted to be concealed within the ground, and a brace member 12 hingedly supported on one end of the receptacle 17, to be concealed therein or supported thereabove.

20 The receptacle 11 is formed of galvanized metal, or other suitable corrosion-resistant material, which is resistant to corrosion when engaged in the ground, as in a cemetery lot. The receptacle 11 is formed with a pair of end walls 14, 15 and a pair of side walls 16 and 17 connected together along their lower edges by a bottom wall 18. The receptacle 11 is open on the upper end or side thereof and when engaged in the ground, the upper edges of the end and side walls are adapted to be positioned substantially flush with the adjacent surface of the ground G, as clearly shown in Figure 4 of the drawings.

25 The bottom wall 18 is formed with a central opening 19 intermediate the length and width thereof, there being formed a depression 20 about the opening 19 for leading water to be drained from the receptacle 11 in order to prevent the accumulation of water or other moisture within the receptacle when the receptacle is closed.

30 A closure member 21 is hingedly mounted on one end wall, as the end wall 15, of the receptacle 11, by a hinge member 22. The closure member 21 is of a length shorter than the total length of the receptacle 11, as clearly noted in the drawings, and is adapted to overlie a portion of the upper open side or end thereof, as clearly shown 35 in the drawings. A suitable handle 24 is swingably mounted on the free edge of the closure member 21, the handle 24 being swingable from an upwardly extending position, as noted in Figures 2 and 4 of the drawings, to a flat position overlying the closure member 21, as clearly noted

in Figure 1 of the drawings. Flanges 25 are formed along the longitudinally extending side edges of the closure member 21 and are adapted to overlie the outer surface of the side walls 16 and 17 in the closed position of the closure member 21. The flanges 25 are spaced apart transversely of the closure member 21 a distance greater than the width of the receptacle 11 and substantially constitute a stop member or limiting means for limiting the swinging of the closure member 21 from a horizontal position overlying the upper open side of the receptacle 11 to a vertically extending or other outwardly extending position of the closure member relative to the receptacle.

A second closure member 26 is hingedly mounted on the other end of the upper open side of the receptacle 11 and is adapted to be swingably supported for swinging from a vertically extending open or extended position to a horizontally extending closed position. In the closed position of the latter closure member 26, the first-mentioned closure member 21 will partially overlie the free, confronting edge of the other closure member 26, as clearly noted in the drawings. The closure member 26 is hingedly mounted on the hinge 27 fixed on the upper free edge of the other end wall 14 and longitudinally extending side flanges 28 are formed on the side edges of the closure member 26 for overlying the outer sides of the upper free edges of the side walls 16 and 17 of the receptacle 11 in the closed position of the closure member 26.

A flat plate or supporting member 29 is fixed on the lower edge of the second-mentioned closure member 26 adjacent the hinge 27, as clearly noted in Figures 1 and 4 of the drawings. The supporting member or plate 29 is extended perpendicularly to the plane of the closure member 26 to be concealed within the receptacle 11 in the closed position of the closure member 26. The supporting plate 29 is of a length greater than the distance between the free edge of the first-mentioned closure member 21 and the hinge 27 for the closure member 26, so that in the open position of the closure member 26, the lower or free edge of the supporting member 29 will overlie the confronting edge of the closure member 21 for supporting the supporting plate in a horizontal position overlying the upper open side of the receptacle 11, as clearly noted in Figure 1 of the drawings.

A flower vase 30 is fixedly supported at the upper side of the supporting member 29 on the lower side of the closure member 26, so that in the extended position of the supporting member 29 and the closure member 26, the vase 30 will be supported in an upwardly extending, vertical position above the receptacle 11, as clearly noted in Figure 1 of the drawings.

For supporting a flag or other pennant on a supporting rod or stick, a suitable brace member 31 is fixedly supported on the under side of the closure member 26 adjacent the vase 30 so that the flag, not shown in the drawings, may have the supporting pole thereof extended through the U-shaped clamp 31, the lower end of the pole to be rested on the upper surface of the supporting member 29.

In the use and operation of the combined cemetery vase and support therefor, the receptacle 11 is initially engaged in the ground with the upper edges of the side and end walls thereof substantially flush with the surface of the adjacent ground G. In the concealed position of

the vase 30, the vase will be disposed horizontally within the receptacle, as clearly noted in Figure 4 of the drawings, the supporting member depending in a vertical position from the horizontally disposed closure member 26. The other closure member 21 is disposed in a horizontal position, as the horizontal closure member 26, the free edge of the closure member 21 partially overlying the free edge of the adjacent edge of the closure member 26, as clearly shown in Figure 4 of the drawings. In this concealed position of the vase 30, the entire assembly 10 is disposed at least flush with the ground, so that mowers, or other agricultural implements employed in the upkeep of the cemetery lot may be suitably passed over the combination 10 and the vase or receptacle will in no manner interfere with the operation of the implement.

When it is desired to extend the vase 30 for supporting flowers by the grave, the closure member 21 is initially raised to an open or partially open position, and the vase 30 is hingedly swung about the hinge 27 to its extended position. The closure member 21 is then replaced in its closed position and the supporting member 29 is lowered to a horizontal position where a portion or lower edge of the supporting member 29 will overlie the adjacent end of the top surface of the closure member 21 for supporting the other closure member 26 in a vertical position, clearly noted in Figure 1 of the drawings, and the vase 30 also in a vertical position for holding the flowers in the desired position.

I do not mean to confine myself to the exact details of construction herein disclosed, but claim all variations falling within the purview of the appended claims.

I claim:

1. In a cemetery vase, a generally rectangular receptacle having an open top, a first closure member hinged at one end on an end of the top of the receptacle to swing downwardly from an elevated open position to a closed position overlying the top of the receptacle, a second closure member hinged at one end to the opposite end of the receptacle to swing downwardly from an elevated open position to a closed position overlying the top of the receptacle, said first and second closure members having means thereon engageable with the receptacle to prevent downward swinging thereof below their closed positions and to maintain said closure members in receptacle closing position, said closure members having free ends and the combined length of said closure members being greater than the length of the receptacle whereby said free ends overlap in the closed positions of said closure members, a support member on and projecting at right angles from the underside of one of said closure members, and a flower urn mounted on said support member and extending generally parallel to said one closure member.

2. In a cemetery vase, a generally rectangular receptacle having an open top, a first closure member hinged at one end on an end of the top of the receptacle to swing downwardly from an elevated open position to a closed position overlying the top of the receptacle, said first and second closure members having means thereon engageable with the receptacle to prevent downward swinging thereof below their closed posi-

tions and to maintain said closure members in receptacle closing position, said closure members having free ends and the combined length of said closure members being greater than the length of the receptacle whereby said free ends overlap in the closed positions of said closure members, a support member on and projecting at right angles from the underside of one of said closure members, and a flower urn mounted on said support member and extending generally parallel to said one closure member, said first closure member being arranged to normally occupy a position with its free edge overlapping the free edge of the second closure member in the closed positions of the closure members, said first closure member having a handle on its upper side adjacent to its free end, said support member and flower urn being on said second closure member whereby said first closure mem-

ber is adapted to be swung upwardly by means of said handle to free said second closure member to be swung upwardly to open position and place the urn in erect position above the receptacle and return said first closure member to closed position, said support member having a free end adapted to rest upon said first closure member to maintain said second closure member in open position.

10
